DESIGN FOR A VANITY CASE OR SIMILAR ARTICLE

David W. Dunberg, New York, N. Y., assignor to Jacques Kreisler Sales Corporation, New York, N. Y.

Application December 3, 1936, Serial No. 66,272

Term of patent 7 years

To all whom it may concern:

Be it known that I, David W. Dunberg, a citizen of the United States, residing at New York, county and State of New York, have invented a new, original, and ornamental Design for a Vanity Case or Similar Article, of which the following is a specification, reference being had to the accompanying drawing forming a part thereof.

Fig. 1 is a plan view of a vanity case showing my new design, arranged with the closure member in open position.

Fig. 2 is a side elevational view thereof, corresponding to the position shown in Fig. 1, with the closure member in closed position.

I claim:

The ornamental design for a vanity case or similar article, as shown and described.

DAVID W. DUNBERG.
